HIGH FREQUENCY TUNED CIRCUITS

Frederic Tom Lett, Syke Ings, Iver, England, assignor to Electric & Musical Industries Limited, Hayes, Middlesex, England, a company of Great Britain

Application July 2, 1938, Serial No. 217,124
In Great Britain July 14, 1937

7 Claims. (Cl. 250—20)

This invention relates to high frequency tuned circuits and has particular reference to the tuned circuits of modulated carrier wave receivers, the frequency band width of which it is desired to vary.

It is well known that damping is imposed on a tuned circuit connected in the grid circuit of a valve when that valve has a largely capacitative load in its anode circuit. The damping, known as the Miller effect, is a function of the magnification factor of the valve and also of its grid to anode capacity.

The object of the present invention is to provide an inexpensive but effective means of varying the selectivity of a tuned circuit in, for example, a wireless receiver provided with a screened grid valve or valves.

According to the present invention in a circuit arrangement including a valve of the screened grid type having a tuned input circuit, in order to vary the selectivity of said tuned input circuit, a condenser connected to the screening grid of the valve is arranged to be connected directly to earth or disconnected therefrom or to be connected to earth through a resistance which may be variable. The condenser may constitute the usual de-coupling condenser and the valve may be a tuned radio or intermediate frequency amplifier or a detector valve, a switch being provided for effecting the changes in the connections to the condenser.

In order that the invention may be more clearly understood and readily carried into effect, a portion of a circuit arrangement embodying the invention will now be described more fully by way of example with reference to the accompanying drawing.

Referring to the drawing a tuned circuit 1 which may be the output circuit of a radio or intermediate frequency amplifier is coupled to the tuned input circuit 2 of a screened grid detector valve 3 provided with a grid leak resistance and condenser 4, 5. The anode 6 of the detector valve is coupled, for example through a resistance and shunt condenser 7, 8, to a low frequency output circuit not shown and the screening grid 9 of the valve is connected through a resistance 10 to a source of high tension voltage. A de-coupling condenser 11 is connected between the screening grid 9 and the cathode 12 through a variable resistance 13 across which is connected a switch 14 which enables the resistance to be short-circuited. This switch may, if desired, be arranged to leave the condenser open circuited.

It will be seen that the arrangement provides for variation of the selectivity of the tuned circuit 2 in a simple manner by operation of the switch 14 to connect the de-coupling condenser 11 directly to the cathode 12 or through the resistance 13. The operating conditions, when the switch 14 is open and the resistance 13 effective, will be modified by the different effective anode impedance which obtains when the switch 14 is closed and the resistance 13 is short circuited. The different anode impedance will produce different damping effects upon the tuned circuit 2 with consequent differences in the breadth of tuning. Adjustment of the value of the resistance 13 provides a finer degree of variation of selectivity. It is possible with the arrangement described to vary the damping applied to the tuned circuit 2 from 10,000 to 250,000 ohms due to the possible variations in the damping effect of the valve.

I claim:

1. A circuit arrangement comprising in combination a thermionic valve having a cathode, an anode, a control grid and a screening grid, a tuned input circuit connected between said cathode and said control grid and means for varying the selectivity of said tuned input circuit, said means comprising a condenser connected to the screening grid of said valve, and means for selectively connecting said condenser directly or through an impedance to the cathode of said valve.

2. A circuit arrangement comprising in combination a thermionic valve having a cathode, an anode, a control grid and a screening grid, a tuned input circuit connecting between said cathode and said control grid and means for varying the selectivity of said tuned input circuit, said means comprising a condenser and a resistance connected in series between the screening grid and cathode, and means for selectively short-circuiting said resistance.

3. A circuit arrangement comprising in combination a thermionic valve having a cathode, an anode, a control grid and a screening grid, a tuned input circuit connected between said cathode and said control grid and means for varying the selectivity of said tuned input circuit, said means comprising a condenser, and a variable resistance connected in series between the screening grid and cathode, and means for selectively short-circuiting said resistance.

4. A circuit arrangement according to claim 1 wherein said valve constitutes an amplifier in a wireless receiver, said condenser being a decou-

- pling condenser for the screening grid of said valve and the selective short-circuiting means comprises a switch.
5. A circuit arrangement according to claim 2 wherein said valve constitutes an amplifier in a wireless receiver, said condenser being a de-coupling condenser for the screening grid of said valve and the selective short-circuiting means comprises a switch.
- 10 6. A circuit arrangement according to claim 1 wherein said valve constitutes a detector valve in

a wireless receiver, said condenser being a de-coupling condenser for the screen grid of said valve and the selective short-circuiting means comprises a switch.

7. A circuit arrangement according to claim 2 5 wherein said valve constitutes a detector valve in a wireless receiver, said condenser being a de-coupling condenser for the screening grid of said valve and the selective short-circuiting means comprises a switch.

10 FREDERIC TOM LETT.
